UNITED STATES PATENT OFFICE.

SAMUEL H. CAMP, OF JACKSON, MICHIGAN, ASSIGNOR TO SAID SAMUEL HIGBY CAMP AND EDWIN C. REYNOLDS, A COPARTNERSHIP, TRADING AS S. H. CAMP & COMPANY.

CORSET AND ABDOMINAL SUPPORT.

Application filed April 22, 1918. Serial No. 229,935.

To all whom it may concern:

Be it known that I, SAMUEL H. CAMP, a citizen of the United States of America, residing at Jackson, in the county of Jackson and State of Michigan, have invented certain new and useful Improvements in Corset and Abdominal Supports, of which the following is a specification, reference being had therein to the accompanying drawings.

10 This invention relates to supporting belt mechanism and refers more particular to mechanism of the type known as abdominal supports formed either as an integral part of the corset or as a separate belt.

15 Among the objects of the invention are to provide a belt or corset support of the character above-mentioned which can be easily applied and more conveniently tightened up than those now in use; to provide a construction which at very slight expense can be incorporated as an integral part of the corset; to so construct and arrange the parts that the pressure or lifting effect is exerted at the parts of the belt or corset where such 25 pressure or lifting is desired; and in general to provide a simple, economical and efficient article of the class described.

The invention also resides in the particular arrangement of the straps and lacing 30 and in such other details of construction and arrangements and combinations of parts as will more fully hereinafter appear.

In the drawings:

Figure 1 is a back plan view of a belt (in 35 extended position) embodying my invention;

Figure 2 is a cross-section on the line 2—2 of Figure 1;

Figure 3 is a view similar to Figure 1 40 showing my invention incorporated in a corset.

Describing in detail the particular embodiment of my invention shown in the drawings, A designates a belt or abdominal support formed of two sections B and B' which are connected at the back by a lacing C in the manner hereinafter described in detail.

At the front the sections B and B' are 50 connected by quick-detachment means, such as loops D and the fasteners E, although the invention is not limited to any particular form of fastening at this point.

The fastening at the front is for the pur-

pose of permitting the belt sections to be 55 disengaged from each other so that the belt can be conveniently put on, but I do not rely upon these fastenings for producing the adjusting or tightening of the belt. For this purpose I employ the lacing C and the strap members F and F' in the following manner: Secured at one side of the belt and preferably toward the front thereof and near the lower edge, as indicated at G, are straps F and F'. These straps are preferably stitched to that portion of the belt in which the stays H are located. These straps extend rearwardly toward the buckles J and J' carried by the short straps or tabs K and K'. The latter are provided with holes L through which the lacing C is preferably wound back and forth in the manner shown in detail in Figure 1. Thus one end of the lacing is secured to the tab section K and extends through one of the holes M' in the section B', then back through one of the holes M on the section B, from there to one of the holes L' in the section K' and then returned to one of the holes M back to one of the holes M' and after passing through the top set of holes in the sections B and B' the lacing is returned back in the opposite direction so that its other end is secured to the tab section K'. By this arrangement the forward movement of the tab sections will produce a leverage sufficient to exert a very strong pull on the sections B and B' toward each other. As the straps F and F' extend diagonally downward this pressure will be produced at the desired part of the belt and also produce a lifting effect.

It will be noticed that the free ends O and O' of the straps F and F' extend through buckles J and J' so that they can be conveniently grasped and pulled toward the front of the belt. This particular arrangement of the straps and belt with reference to the lacing and the main body sections of the belt is an important feature, in that it makes the tightening of the belt much more convenient than in previous constructions. The buckle is, of course, of the well-known type in which after the strap is once tightened up it will be automatically held in this position until released. Therefore in applying the belt it is only necessary for the wearer to draw the free ends Q and Q' of the main body sections together at the front

and engage the fastening devices D and E, after which the free ends O and O' of the straps are pulled toward the front until the pressure desired is obtained. Moreover by 5 this arrangement no adjustment of the side straps or the lacing is necessary in applying or taking off the belt unless desired.

Another important feature of my invention is the fact that the structure is peculiarly 10 adapted to be incorporated in the ordinary corset construction, either as an integral part thereof or as an attachment device. One such embodiment of the invention is 15 shown in Figure 3 in which R and R' designate the main body sections of the corset which are connected at the front by quick-detachable means R² and R³. At the back the sections R and R' are provided with loop 20 openings R⁴ and R⁵ respectively through which the lacing is ordinarily extended. However, in place of employing the ordinary lacing throughout the entire length, I 25 preferably employ only a short lacing S at the upper end and incorporate the belt feature, previously described, in the central and lower portions. Thus the section R is provided with a strap T and the section R' with a strap T' which are connected by 30 buckles T² and T³ to tabs connected to the end of the lacing S' in the same manner as the straps, tabs and lacing are connected in the construction shown in Figure 1. At 35 the lower part of the corset construction there is employed a similar set of straps V and V' connected to lacing S², the free ends of both the straps T and T' and B and B' extending toward the front in the manner 40 previously described. Neither construction however is necessarily limited to the fastening devices being limited at the front, as it is obvious that a side opening construction could also be employed. However, in both 45 the belt and the corset arrangement the advantages of a back lacing while retaining the necessary lifting effect at the front is

obtained and the construction is one that can be quickly and conveniently applied.

While I have shown the belt feature as being embodied at the middle and lower parts of the corset it is of course possible to 50 use the same construction in the upper part and also to have a greater or lesser number of straps and lacing. I therefore do not desire to limit the invention to the particular structure shown nor to the details of 55 construction and combinations of parts except as ultimately set forth in the claims.

What I claim as my invention is:—

1. In a device of the class described, the combination with a pair of separate sections having quick-detachment means at the front edges thereof, of a lacing connecting the adjacent rear edges of said sections, a pair of tab members movable over said sections near the adjacent rear edges thereof, 60 one end of said lacing being secured to one of said tab sections, the opposite end of said lacing being secured to the other of said tab sections, the intermediate portions of said lacing freely movably engaging said tab 65 members and the adjacent rear edges of said sections, buckles respectively carried by said tab members, and adjusting means permanently secured to the respective sections and return-bent through said buckles. 70

2. In a device of the class described, the combination with a pair of separate sections having quick-detachment means at their front edges, of a lacing connecting the adjacent rear edges of said sections, a pair of tab members movable over said sections near the adjacent rear edges thereof and freely 75 movably engaged by said lacing, buckles respectively carried by said tab members, and a pair of adjusting straps permanently secured to the respective sections and return-bent through said buckles. 80

In testimony whereof I affix my signature.

SAMUEL H. CAMP.
